CLAIM

The ornamental design for a miniature inline sensing device for continuous measurement of fluid properties, as shown and described.

DESCRIPTION

FIG. 1 is a front top perspective view of the miniature inline sensing device for continuous measurement of fluid properties;

FIG. 2 is a front elevational view of the miniature inline sensing device for continuous measurement of fluid properties of FIG. 1;

FIG. 3 is a rear elevational view of the miniature inline sensing device for continuous measurement of fluid properties of FIG. 1;

FIG. 4 is a right side elevational view of the miniature inline sensing device for continuous measurement of fluid properties of FIG. 1;

FIG. 5 is a left side elevational view of the miniature inline sensing device for continuous measurement of fluid properties of FIG. 1;

FIG. 6 is a top plan view of the miniature inline sensing device for continuous measurement of fluid properties of FIG. 1;

FIG. 7 is a bottom plan view of the miniature inline sensing device for continuous measurement of fluid properties of FIG. 1; and,

FIG. 8 is a rear bottom perspective view of the miniature inline sensing device for continuous measurement of fluid properties of FIG. 1.

The broken-line disclosure of elements is understood to represent portions of the article in which the design is embodied, but which form no part of the claimed design.

1 Claim, 7 Drawing Sheets
